UNITED STATES PATENT OFFICE.

HARRY ROGOVIN, OF BROOKLYN, NEW YORK.

DESIGN FOR A BED-LAMP SHADE.

Application filed April 14, 1926. Serial No. 17,300. Term of patent 3½ years.

To all whom it may concern:

Be it known that HARRY ROGOVIN, a citizen of the United States, and resident of New York city, in the county of Kings, borough of Brooklyn, and State of New York, has invented a new, original, and ornamental Design for Bed-Lamp Shade, of which the following is a specification, reference being had to the accompanying drawing, forming part thereof, in which the figure is a perspective view of a lamp shade embodying my new design.

I claim:

The ornamental design for a bed-lamp shade as shown.

Dated this 6th day of April 1926.

HARRY ROGOVIN.
